United States Patent Office.

HENRY BLAKE, OF RINDGE, AND AMOS J. BLAKE, OF FITZWILLIAM, NEW HAMPSHIRE.

Letters Patent No. 96,301, dated November 2, 1869.

IMPROVEMENT IN MACHINE FOR SHAPING WOODEN TRAYS.

The Schedule referred to in these Letters Patent and making part of the same.

To all whom it may concern:

Be it known that we, HENRY BLAKE, of Rindge, in the county of Cheshire, and State of New Hampshire, and AMOS J. BLAKE, of Fitzwilliam, in said county and State, have invented a new and useful Improved Machine for Cutting and Shaping Wooden Trays; and we do hereby declare that the following is a full, clear, and exact description of the same, reference being made to the accompanying drawings, making a part of this specification—

Figure 1 of which is a plan or top view of the machine, as it is arranged for cutting the inside of the trays.

Figure 2 is a side view.

Figure 3 is a front view of the same.

Figure 4 is a top view of a supplementary table or carriage for shaping the outside of the trays.

Figure 5 is the end view of the same.

The nature of our invention consists of an arrangement of mechanism for holding and presenting blocks or bolts of wood for the action of revolving cutters, in such a manner as to insure the shaping of a concave or convex form, such as may be desired; the said cutters being made to traverse the blocks by suitable reciprocating or vibratory movements of the mechanism, guided by a model or pattern, to produce a properly-shaped tray, which will only require the application of a smoothing-tool to fit it for sale or use.

To enable others skilled in the art to use our invention, we will proceed to describe its construction and operation.

Like letters of reference refer to like parts of the machine.

The principal frame-work of the machine is represented by the letter A, in the drawings, and B is a revolving shaft, suspended by said frame, and provided with pulleys for the driving-band, from any suitable motor, and for communicating motion to the cutters C C, which are attached to a swinging frame D, the position of which is governed by a tracing-wheel E, as it rolls upon the model or pattern F, so as to produce a similar form from the blocks acted upon by the cutters.

G is a carriage, having a reciprocating motion from crank H.

It is provided with supplementary tables or carriages R' and R'', which are severally adapted for cutting the concave and convex sides of the trays, either being used for its specific purpose, as may be desired.

* On the supplementary table or carriage R'', used for shaping the outsides of the trays, is an elevated platform, U, above its general face or plane, on which the blocks and model are secured.

This arrangement allows the saws or cutters to pass down and cut over the outsides, to the lower edge of the same.

As this result could not be attained by securing the blocks and model to the surface of a level table or carriage, it is an important auxiliary to our machine.

To these supplementary tables are secured, by means of suitable dogs or clamps, the tray-blocks or bolts I I, also the model or pattern F, and in addition to the transverse reciprocating motion of the carriage G, these supplementary tables or carriages R' R'', sliding on the same, have also a movement in a longitudinal direction, effected by means of a ratchet-rack, L, and pawl M, which are worked by cams or inclined planes, attached to frame A, so that the cutters are made to traverse the blocks I I, throughout their entire length, taking a new line of cut at each passage across the same, removing therefrom the surplus material, and reducing them to correspond with the model.

V is a cam, for liberating the pawl M from the ratchet L, thus detaching the tables R' or R'', which, after suspending the motion of the crank H, may, by hand-crank N, rack S, and pinion T, be moved quickly in either direction, so that the cutters may be made to traverse the blocks in the direction of their length, to remove any ridges or inequalities which may have been left by their passage in the other direction, the movement from the crank H being temporarily suspended.

This arrangement for recutting at right angles to the previous cut, is very useful in smoothing the surface of the work, and facilitating the whole operation.

O is an adjustable plate or rest, for the tracing-wheel E, which is set to form a continuation of the model to support and guide the cutters properly, as they pass off the blocks on either side.

P is an equivalent arrangement for the convex sides of the trays.

The operation of the machine is as follows, viz:

The blocks to be cut are secured in their places on the tables R' or R'', together with the model which it is desired to duplicate, so that the tracing-wheel E will be at one end of the same. The crank H is then put in motion, and the carriage G passes the blocks back and forth underneath the cutters, while the pawl and rack set the upper tables R' or R'' ahead in another direction at each stroke of the said lower carriage G, until the entire surface of the blocks has been presented for the action of the cutters, which cutters, guided by a perpendicular movement of the swinging frame D, from the tracing-wheel and model, reproduce its form in the blocks I I.

The cutters C C may be made in form of circular saws or in the form of a plane-head or otherwise, and the movements of the reciprocating carriage G may be produced by different means than those described, to effect the same object.

We make no claim to the use of a model or pattern for the guidance of cutters to produce a similar form; but

We do claim as our invention, and desire to secure by Letters Patent—

1. Hanging the cutters C C, and tracing-wheel E, a sufficient distance below the swinging frame D, to allow a free passage of the carriages R' and R", while carrying the tray-blocks I I and model F underneath the same, substantially as herein shown and described, and for the purpose set forth.

2. The arrangement of the adjustable table or rest O, in combination with the carriage R', substantially in the manner herein shown and described, and for the purpose set forth.

HENRY BLAKE.
AMOS J. BLAKE.
